UNITED STATES PATENT OFFICE.

AXEL F. LARSON, OF CHICAGO, ILLINOIS, ASSIGNOR OF ONE-HALF TO
C. F. LARSON, OF CRYSTAL FALLS, MICHIGAN, AND OSCAR K. OSTER-
GREN, OF CHICAGO, ILLINOIS.

AUTOMATIC PIANO-PLAYER.

SPECIFICATION forming part of Letters Patent No. 792,055, dated June 13, 1905.

Application filed May 28, 1904. Serial No. 210,235.

To all whom it may concern:

Be it known that I, AXEL F. LARSON, a citizen of the United States, residing at Chicago, in the county of Cook and State of Illinois, have 5 invented a certain new and useful Improvement in Automatic Piano-Players, (Case No. 5,) of which the following is a full, clear, concise, and exact description, reference being had to the accompanying drawings, forming 10 a part of this specification.

My invention relates to automatic piano-players, and relates more particularly to improvements in devices of this character by means of which the parts are made readily 15 accessible for adjustment and repair and by means of which the construction of the instruments may be simplified and reduced in cost.

Various improvements will hereinafter be more fully pointed out by reference to the accompanying drawings, in which—

Figure 1 illustrates in front elevation a piano-player constructed in accordance with my invention. Fig. 2 is a partial cross-sectional view taken on lines 2 2 of Fig. 1 and 25 Fig. 3. Fig. 3 is a cross-sectional view taken on line 3 3 of Fig. 2. Fig. 4 is a cross-sectional view taken on line 4 4 of Fig. 2, parts being broken away to more clearly illustrate the interior construction. Fig. 5 is a cross-30 sectional view illustrating the construction of an expression-bellows, the purpose of which will more fully appear. Fig. 6 is a cross-sectional view of a regulating-bellows employed to control the supply of power to the motor 35 which drives the mechanism, and Fig. 7 is a plan view of a primary-pneumatic block.

The foundation-board 11 is preferably a three-ply board, in which the channels to be hereinafter explained may easily be formed. 40 Below this foundation-board are mounted a pair of suction-bellows 12 12, each bellows being provided with an inlet-valve 13 and an outlet-valve 14, these valves consisting, essentially, of a series of openings through the top 45 and bottom boards of the bellows, over which a strip of leather or other suitable material is held by means of a thin sheet of springy metal, as shown in Fig. 2 and as described

also in my copending application, Serial No. 175,107, filed September 30, 1903. The torsional spring at 15' tends normally to maintain each power-bellows in a closed or collapsed condition. The treadles 15 and 16 are connected, by means of the straps 17 and 18, to the bottom boards of the power-bellows 55 and when depressed serve to open the bellows, thereby creating a suction, which withdraws air from the main bellows 19 by way of the inlet-valves 13. The subsequent collapse of the power-bellows 12 causes the expulsion of 60 air through the outlet-valves 14. A suitable spiral spring is fastened at 20 to a block 21, rigidly mounted upon the foundation-board 11, the other end of this spring being fastened at 22 to one lever-arm, 23, of a bell-crank 65 lever 24, which is pivoted at 25 by means of a bracket 26, rigidly secured to the foundation-board, and the other lever-arm, 27, which supports the top board 28 of the main bellows 19 by means of a small roller 29, fastened 70 to a bracket 30, which is secured to the top board 28. Spring mechanism of this character is provided at either side of the main bellows. It will be seen that as the main bellows is collapsed and the top board 28 drawn downward toward the foundation-board 11 the roller 29 will bear upon the lever-arm 27, causing its depression and the lever to swing about the pivot 25, thereby causing the extension of the spring 31. The depression of 80 the top board 28 of the main bellows is resisted not only by the increasing tension of the spring 31 as it is extended in length, but also on account of the decrease in length of the lever-arm 27 between the pivot and the 85 point of contact with the roller 29.

The operation of all of the mechanism of the automatic player is caused by suction, and the air which is used in the operation of the various parts all passes through this main bellows 19. A pair of channels 32 32 lead from the openings 33 33 at the treble side of the main bellows to the treble-regulating chamber 34 by way of the openings 35 35. The hinged valve 36 is provided with a leather face 95 for the purpose of closing the openings 35 35,

This valve is provided with a retracting-spring 37, passing to the top of the valve and the interior of the regulating-chamber, and tends to maintain the valve in an open position. A 5 similar pair of channels 38 38 lead from the openings 39 39 in the main bellows through the foundation-board to the openings 40 40, leading into the bass-regulating chamber 41. These openings 40 40 are provided also with 10 a hinged valve 42, the retracting-spring 43, attached to the upper side of the valve, tending to maintain the valve in an open condition.

Assuming that the valves 36 and 42 are open, it will be seen that the withdrawal of air from 15 the main bellows 19 creates a partial vacuum within the treble-regulating chamber 34 and the bass-regulating chamber 41. Means are provided, as will hereinafter more fully appear, for the purpose of regulating and controlling the pressure within these chambers. 20 The partition 44 serves to divide the chamber 34 from the chamber 41. These chambers are divided one from the other, for the reason that the pressure in one chamber controls the 25 strength with which the treble-keys are struck, while the other controls the strength with which the bass-keys are struck, and means are provided by which either may be controlled independently of the other.

30 The air-tight action-chambers 45 and 46 are divided by means of the partition 47. The chamber 45 is connected with the treble-regulating chamber 34 by way of a plurality of channels 48 48, and the action-chamber 46 is connected with the bass-regulating chamber 41 by way of the channels 49 49. Through 35 these channels the air is exhausted from the action-chambers through the regulating-chambers into the main bellows.

40 At 50 I have shown a well-known form of tracker-board provided with a series of fine openings 51, over which the note-sheet 52 is drawn by means of the roller 53, the note-sheet being simultaneously unwound from the 45 spool 54. As is well understood by those skilled in the art, this note-sheet is provided with openings corresponding with the keys to be struck, these openings registering with the channels 51 of the tracker-board. Each channel in the tracker-board is provided with a tube 55 to afford connection with the associated primary pneumatic. One of the channels 51 in the tracker-board is shown in cross-section in Fig. 2, and the tube 55, leading from 50 the lower end of this channel, connects with a small brass tube 56, inserted at the front of the primary-pneumatic rack 57. A channel 58 leads from this brass tube 56 through the primary-pneumatic rack to a small brass tube 59, which registers with a small hole (60 of Fig. 55) which connects with the primary-pneumatic chamber 61 of the primary-pneumatic block 62. As best illustrated in Fig. 4, a series of these 60 primary-pneumatic blocks is attached to the primary-pneumatic rack by means of the

screws 63 or other suitable connecting members. A small passage-way 64 leads from each channel 58 to the action-chamber 45, the size of the opening being regulated in each case by an action-regulating screw 65. The suction within the main bellows and acting through the regulating-chamber 34, the channels 48, and the action-chamber 45 serves to withdraw air from the channel 58, the tube 55, and the associated channel 51 of the tracker-board when the opening at the top of the tracker-board is covered by the note-sheet 52. Thus there is created within the primary-pneumatic chamber 61 a vacuum, or at least a partial vacuum, corresponding in pressure with that in the action-chamber 45. The stem 66 of the action-controlling valve 67 is screw-threaded into the nut 68, secured to the piston-like leather washer 69 of the primary pneumatic, this washer being more similar to a piston in 85 action than in construction. The valve 67 is secured in position upon the screw-threaded stem 66 by means of small leather lock-nuts 70 71. The stem is guided in its longitudinal movements by means of a slender cross-bar 72, which, however, does not entirely close the opening 73 at the upper side of the valve-chamber 74. The opening 75 in the lower side of the valve-chamber 74 connects with the interior of the action-chamber 45. When in 90 its normal position, the valve 67 serves to close this opening 75, and when actuated by means of the leather washer 69 the valve-stem 66 forces the valve 67 upward against the periphery of the opening 73 at the top of the 95 chamber 74. This action may be explained as follows: When an opening in the note-sheet 52 registers with the opening at the top of the channel 51 in the tracker-board, air is admitted by way of the tube 55 to the channel 100 105 58, and as the opening provided by means of the regulating-screw 65 in the channel 64 is comparatively small the air cannot be exhausted from the channel 58 to such an extent as to maintain the pressure within the channel 58 of the same low degree as in the chamber 45. There being created in this manner a greater pressure on the lower side of the washer 69 of the primary pneumatic than on the upper side, the stem 66 is forced rapidly 110 upward, carrying with it the valve 67, which produces an opening between the channel 76 and the chamber 45 by way of the port 75 and which causes almost simultaneously the closure of the opening between the channel 76 115 and the outside atmosphere by way of the port 73 at the upper side of the valve-chamber 74. The channel 76 leads through the front board 77 to the interior of an action-bellows 78, the lower board 79 of this bellows 120 carrying the striking-lever 80, this lever swinging upon the hinge 81, which serves also as the hinge for the bellows itself, and being guided at one end by means of a staple-like guide 82, fastened to the back board 77 and 125 130

extending within a small slot (not shown) cut in the extremity 83 of the lever 80. The lever 80 when in its normal position rests upon a thin felt cushion 84. A striking-finger 85 is adjustably secured to the rear end of the lever 80. It is these fingers 85, secured to the rearward ends of the levers 80, which strike the keys of a piano or other instrument of like nature. The top boards of the action-bellows are secured to the mounting-boards 86, which extend from end to end of the piano-player.

The interior of the bellows 78 is connected normally with the atmosphere by way of the channel 76 and the port 73 in the top of the chamber 74. When, however, the valve 67 is thrust suddenly upward, due to the registration of an opening in the note-sheet with the associated channel in the tracker-board, this atmospheric connection is closed and the air is suddenly withdrawn from the action-bellows 78 by way of the channel 76, the port 75, the action-chamber 45, the channels 48, the regulating-chamber 34, the channels 32, the main bellows 19, the valve 13, the power-bellows 12, and thence through the escape-valve 14 to the atmosphere. The suction thus created within the bellows 78 causes a sudden collapse thereof, whereupon the associated finger 85 is caused to strike the registering key of the piano in front of which the player is placed. When the note-sheet again closes the opening in the tracker-board, air is withdrawn from the channel 58 by way of the small passage-way 64, thus rapidly reducing the pressure in the chamber 61 below the primary pneumatic 69. The valve 67 thereupon closes the port 75 and opens the port 73, permitting the access of atmospheric pressure to the action-bellows 78, which is at once distended. The other primary pneumatics and the associated valves are mounted upon the primary-pneumatic rack and the boards which form the action-rack 86 in the manner already described in connection with the mechanism shown in the full lines in the cross-section of Fig. 2.

It will be seen that the arrangement of the valve mechanism employed affords an exceedingly easy means of removal for replacement or repair. In order to remove a primary pneumatic and its valve, it is but necessary to remove the boards 87 and 88, one or both, from the back of the action-chamber and the space behind the action-valves, whereupon the top plate 89 may be removed from the valve-chamber 74, thus permitting the stem 66 to be unscrewed from the button 68, which is glued to the leather washer 69. The valve and its stem may thus be removed through the top of the valve-chamber, while the screws 63, which retain the primary - pneumatic block 62 in place, are withdrawn to permit the removal of the block from its position in register with the brass tube 59.

It will be noted that each of the primary

pneumatics and its associated valve mechanism is a duplicate of each of the others and that the primary-pneumatic blocks 62 are of identical construction, whereby these blocks may be made interchangeable, any block fitting in the place occupied by any other. The arrangement shown is economical of space and permits this compact arrangement without sacrificing easy access to all of the movable parts. The construction, furthermore, is of the utmost simplicity and provides a player of low cost of manufacture. The construction of the device is preferably such that the back board 87, together with the boards 86, which constitute the valve-rack, may be bodily removed from the rack 57, to which the primary-pneumatic blocks are secured. The arrangement, furthermore, provides for air-tight chambers of exceedingly small capacity, whereby these chambers may be constructed in a simple yet efficient manner and at very low cost. Only a comparatively few screws are required to retain the cover 88 in place upon the action-chambers 45 and 46, and but few screws are required to secure the valve-rack 86 and the back board 77 in place above the rack for the primary pneumatics.

In Fig. 1 there is illustrated somewhat diagrammatically at 90 a motor which causes the movement of the note-sheet across the tracker-board 50. This motor may be of the construction shown in my copending application, Serial No. 165,349, filed July 7, 1903. The motor is provided with gearing (not shown) by means of which the same motor running always in the same direction may serve to rotate the roller 53 in the direction indicated by the arrow 91 when playing and also to cause the rotation of the roller 54 in the direction indicated by the dotted arrow 92 for rewinding the note-sheet upon the spool 54. The motor 90 is operated by suction, the air being withdrawn from the motor-bellows by means of the tube 93, leading to the motor-regulating bellows 94. This tube may be led through the case 95 in any suitable position. The interior of the motor-regulating bellows 94 is connected, by means of the channel 96, with the main bellows 19, the channel being provided at one end with the opening 97, which opens into the main bellows 19, and at the other end with two openings, the opening 98 leading directly to the interior of the bellows 94 and the other opening 99 being covered by a hinged valve 100, this valve being provided with a leather face for covering the opening 99. The top board 101 of the bellows 94 is provided also with a valve-cover 102, this valve being provided with a leather face for covering the opening 98. The valve 100 is provided with a retracting-spring and normally covers the opening 99. When suction is created within the main bellows 19, air is withdrawn from the bellows 94 by way of the opening 98 and the channel 96. The suction thus created

within the bellows 94 causes the downward movement of the back board 101 against the tension of the flat spring 103 until the valve 102 is brought into contact with the opening 98. This of course prevents the further withdrawal of air from the bellows; but as air may enter the bellows by way of the tube 93, leading from the motor, pressure within the bellows is at once increased, thereby permitting the retraction of the valve 102, together with the top board 101, by means of the spring 103. This again opens the passage to the channel 96, whereby air may be again withdrawn from the bellows 94. The result of the construction is that the tension of the spring 103 can be regulated by means of the screw 104, bearing upon the upset end 105 of the spring, whereby the pressure within the bellows 94 is regulated to produce the desired degree of suction upon the motor-bellows.

The degree of suction or pressure within the treble-pressure-regulating chamber 34 is or may be controlled by an expression-bellows 106. This bellows is illustrated in cross-section in Fig. 5 and consists of a bottom board 107, secured to the foundation-board 11, and through which an opening 108 leads by way of a channel 109 and an opening 110 to the main bellows 19. Another opening 111 leads by way of a channel 112 to an opening 113 in the foundation-board 11 within the regulating-chamber 34. The opening at this end is covered by a hinged valve 114, the valve being provided with a retracting-spring 115. The withdrawal of air from the expression-bellows 106 to the main bellows 19 causes the collapse of the bellows, thereby causing the top board 116 of the bellows to move downward against the tension of the retracting-spring 117, causing the leather-faced valve 118 to more or less completely cover the opening 108 leading by way of the channel to the main bellows 19. The tension of the spring 117 may be adjusted by means of the screw 119, whereby the pressure within the expression-bellows 106 may be regulated. By closing the valve 36, which controls the opening leading directly to the main bellows 19, the withdrawal of air from the treble-regulating chamber 34 may be accomplished only through the opening 113, the channel 112, and the expression-bellows 106 and thence through the channel 109 to the main bellows 19. The pressure within the treble-regulating chamber 34 is therefore, as great as that within the expression-bellows 106, which is materially less than within the main bellows 19—that is to say, the degree of suction exerted upon the parts connected with the treble-regulating chamber 34 is considerably less when the passage of air must be accomplished by way of the expression-bellows 106 than when it may be accomplished directly through the channels 32, as previously described. When, therefore, it is desired that

softly while the bass portion of the scale is played more heavily, the operator depresses the button 120, this button being connected by way of the stem 122 to the crank-arm 123 of a lever whose other arm 124 normally rests above a pin 125, projecting from the movable end of the hinged valve 36. The depression of this button causes the crank-arm 124 to press upon the pin 125, thereby maintaining the valve 36 in a closed condition and preventing the egress of air from the treble-regulating chamber 34 to the main bellows 19 by way of the channels 32. The withdrawal of air from the treble-regulating chamber 34 must be accomplished, therefore, only by way of the expression-bellows 106. A similar expression-bellows 126 is provided for the bass portion of the action. This bellows is connected with the main bellows by way of a channel 127, connecting the openings 128 and 129, respectively placed within the expression-bellows 126 and the main bellows 19. Another opening 130 connects with a channel 131, which leads to an opening 132 within the bass-regulating chamber 31, the opening 132 being covered by a valve 133, provided with a retracting-spring 134. When it is desired to decrease the strength of movement of the action-bellows which controls the fingers actuating the keys in the bass portion of the scale, the button 134 is depressed, this button being connected by way of the stem 135 with the crank-arm 136 of the lever, whose shorter crank-arm 137 rests above the pin 138, projecting from the movable end of the valve 42. A depression of this button 134 closes the valve 42 in the manner which will be understood by those skilled in the art, thereby preventing the passage of air from the chamber 41 to the main bellows 19 by way of the channels 38 and causing the passage of air to the main bellows 19 only by way of the opening 132, the channel 131, the opening 130, the expression-bellows 126, and the channel 127, leading to the main bellows. The construction of the expression-bellows 126 is similar to that shown in Fig. 5, and the downward movement of the top board of the bellows against the tension of the retracting-spring 134 so regulates the degree of suction within the regulating-chamber 41 that upon the depression of the button 134 and the closure of the valve 42 the keys in the bass portion of the scale are struck only with that degree of strength permitted by the adjustment of the retracting-spring associated with the expression-bellows 126. The speed or tempo with which the note-sheet is moved across the top of the tracker-board is controlled by means of a lever 139, which is connected, by means of the rod 140 and the lever 141, with a throttle-valve in the suction-pipe 93, leading to the motor.

As is well understood by those skilled in the art, it is desirable in automatic piano-players of this character to rewind the note-sheet

upon the spool 54 after having been passed over the tracker-board in playing the music for which the note-sheet is adapted. Within the case which contains the motor 90 there is 5 a clutch mechanism controlled by the lever 142. This lever is connected, by means of the rod 143, with the manual or controlling lever 144. A movement of this lever to its right-hand position connects the motor 90 with the rollers in such a way that the roller 53 is rotated 10 in the direction indicated by the arrow 91, this being the direction of rotation during which the music is played. The lever 144 is connected, by means of the rod 145, the bell- 15 crank lever 146, and the rod 147, with the crank-arm 148 of a rock-shaft 149, this shaft being provided with the cranks 150, 151, 152, 153, and 154. A depression of the crank-arm 148, due to the movement of the lever 144 to 20 its left-hand position, causes a downward movement of all of the cranks associated with the rock-shaft 149, the crank 150 engaging the pin 155 of the valve 133, the crank 151 engaging and depressing the pin 138 of the 25 valve 42, the crank-arm 152 depressing the pin 125, and thus its associated valve 136, and the crank 153 depressing the valve 114 by means of its pin 156. The closure of all of these valves prevents the withdrawal of air from 30 the regulating-chambers 34 and 41, and this prevents the operation of the pneumatics and action as has heretofore been described. At the same time the depressed crank 154 engages a crank 157, connected by way of the shaft 35 158 with the crank 159. The depression of the crank 157 causes a corresponding upward movement of the crank 159, this crank engaging the lower side of the pin 160 of the valve 100, thereby opening this valve and permitting 40 the free passage of air from the pipe 93 to the main bellows 19 without the intervention of the control afforded by means of the motor-regulating bellows shown in Fig. 6.

The strength with which the keys are struck 45 may be controlled to a certain degree by means of the lever 144. A movement of this lever to the left limits the degree to which the valves in the regulating-chambers may be opened by their retracting-springs. When the lever 144 50 is moved to its extreme left-hand position, the valve 100 in the motor-controlling bellows is opened; but a considerable closure of all of the valves through which air is exhausted from the regulating-chambers may be effected 55 by means of the rotation of the regulating-shaft 149 before the valve 100 of the motor-controlling bellows is opened—that is, the cranks with which the shaft 149 is provided depress the pins they engage to a considerable degree before a crank 154 is brought into engagement with the crank 157.

In Fig. 4 the tops of the action-valves are shown, the action-valve rack being broken away at the center of the figure to show the

primary pneumatics and the screws for regulating the speed of the action. 65

As will be well understood by those skilled in the art, the automatic piano-player of my invention may be provided with such other equipment as is common to instruments of this class—such, for instance, as manually-controlled mechanism for operating the pedals of a piano. Furthermore, the construction and mode of operation of the expression-bellows may be modified as desired without departing 70 from the spirit of my invention. In fact, I have herein shown but a preferred embodiment of my invention, many modifications of which may be employed without departing 75 from the spirit of my invention. I do not 80 wish, therefore, to limit myself to the precise construction herein set forth; but,

Having described my invention, I claim as new and desire to secure by Letters Patent—

1. In an automatic piano-player, the combination with a plurality of action-bellows, each controlling a key-actuating lever, of an action-valve for controlling the actuation of each action-bellows, and a primary pneumatic associated with each action-valve, said action-valves and the associated primary pneumatics being arranged in horizontally and vertically staggered rows. 85

2. In an automatic piano-player, the combination with a plurality of action-bellows, of an action-valve for controlling the actuation of each action-bellows, and a primary pneumatic associated with each action-valve, said action-valves being arranged in horizontally and vertically staggered rows. 90

3. In a device of the class described, the combination with a plurality of action-bellows each controlling the actuation of a key of the instrument to be played, of an action-valve for controlling the actuation of each action-bellows, and a primary pneumatic associated with each action-valve, said primary pneumatics being arranged in vertically and horizontally staggered rows. 100

4. In an automatic piano-player, the combination with a plurality of action-valves, of a plurality of primary pneumatics, one for each action-valve, a plurality of primary-pneumatic blocks upon each of which one of said primary pneumatics is mounted, and a primary-pneumatic rack to which said blocks are attached and from which any one block may be removed without the removal of any other block. 110

5. In a device of the class described, the combination with a plurality of action-valves, of a primary pneumatic for controlling each valve, a primary-pneumatic block upon which each primary pneumatic is mounted, a primary-pneumatic rack having a plurality of steps, and a row of primary-pneumatic blocks mounted upon each step of said rack. 120

6. In a device of the class described, the com-

bination with a plurality of action-valves, of a primary pneumatic for controlling each valve, a primary-pneumatic block upon which each primary pneumatic is mounted, a primary-pneumatic rack having a plurality of steps, and a row of primary-pneumatic blocks mounted upon each step of said rack, the primary-pneumatic blocks on one step of the rack being offset with respect to the primary-pneumatic blocks on another step of the rack.

7. In a device of the class described, the combination with a plurality of action-valves, of a primary pneumatic for controlling each valve, a primary-pneumatic block upon which each primary pneumatic is mounted, a primary-pneumatic rack having a plurality of steps, a row of primary-pneumatic blocks mounted upon each step of said rack, the primary-pneumatic blocks on one step of the rack being offset with respect to the primary-pneumatic blocks on another step of the rack, and a channel leading through said rack to the said primary pneumatics.

8. In a device of the class described, the combination with a primary-pneumatic rack having a plurality of steps, of an action-chamber of which said steps form one wall, a plurality of primary-pneumatic blocks upon each of which is mounted a primary pneumatic, a row of said blocks being mounted upon each of the steps of said rack, and a plurality of offset channels formed in said rack and each registering with an opening in one of said primary-pneumatic blocks.

9. In an automatic piano-player, the combination with a plurality of action-bellows, of a vertical front board, a stepped rack adjacent to said front board, an action-valve for each action-bellows mounted upon said rack, there being channels formed in said rack and said front board, one leading from each action-valve to the associated action-bellows, a stepped primary-pneumatic rack, and a plurality of primary pneumatics each mounted upon a primary-pneumatic block, a row of blocks being secured to each step of the primary-pneumatic rack and each having an opening registering with a channel in said rack, said channels being connected with the tracker-board.

10. In a device of the class described, the combination with a plurality of action-bellows, of a vertical front board, a stepped rack adjacent to said front board, and an action-valve for each action-bellows mounted upon the rack, there being channels formed in said rack and said front board, one leading from each action-valve to the associated action-bellows.

11. In an automatic piano-player, the combination with a tracker-board, of a stepped primary-pneumatic rack, a plurality of primary pneumatics, each mounted upon a primary-pneumatic block, a row of blocks being secured to each step of the rack and each hav-

ing an opening registering with a channel in said rack, a tube extending from the terminal of each of said channels to an opening in the tracker-board, and a regulating-screw for each of said primary pneumatics, the heads of the regulating-screws being interposed between said tubes.

12. In a device of the class described, the combination with a stepped primary-pneumatic rack, of a plurality of primary pneumatics, each mounted upon a primary-pneumatic block, a row of said blocks being secured to each step of the rack, an action-chamber of which said rack forms a wall inclosing said primary pneumatics and their blocks, and suitable channels leading through the stepped rack by means of which air may be withdrawn from the action-chamber.

13. In an automatic piano-player, the combination with a stepped primary-pneumatic rack, of a plurality of primary pneumatics, each mounted upon a primary-pneumatic block, a row of blocks being secured to each step of the rack and each having an opening registering with a channel in said rack, said channels being connected with the tracker-board, an action-chamber in which said primary pneumatics are located, and suitable channels leading through said stepped rack by means of which the air may be withdrawn from said chamber, these latter channels being offset with respect to the channels connected with the tracker-board.

14. In an automatic piano-player, the combination with a stepped primary-pneumatic rack, of a plurality of primary pneumatics, each mounted upon a primary-pneumatic block, each primary pneumatic and its block being identical with all others, a row of said blocks being secured to each step of the rack and each having an opening registering with a channel in said rack, said channels being connected with the tracker-board, and an action-chamber inclosing said primary pneumatics, said chamber having a removable rear wall affording access to all said primary pneumatics and their blocks.

15. In an automatic piano-player, the combination with a main bellows, of a regulating-chamber, a channel leading from the main bellows to the regulating-chamber, a valve for throttling the opening in said channel, a spring tending to maintain said valve in an open condition, lever mechanism to limit the degree to which said spring may open said valve, and additional means to close said valve.

16. In combination with a main bellows, a treble-regulating chamber, a bass-regulating chamber, a channel leading from the main bellows to each of said regulating-chambers, a valve for each of said channels for throttling the opening therein, springs tending to maintain said valves in an open condition, lever mechanism adapted to limit correspondingly the degree to which said springs may

open said valves, and additional mechanism associated with each valve by means of which either may be closed without affecting the other.

5 17. In a device of the class described, the combination with a main bellows, of a regulating-chamber, a channel leading from the main bellows to the regulating-chamber, a valve for throttling the opening in said channel, a spring tending to maintain said valve in an open condition, means to limit the degree to which said spring may open said valve, additional mechanism to close said valve, a second passage-way leading from said main bellows to said regulating-chamber, and expression-regulating mechanism included in said second passage-way.

10 18. In an automatic piano-player, the combination with a main bellows, of a treble-regulating chamber, a bass-regulating chamber, a channel leading from each regulating-chamber to the main bellows, a valve for each of said channels for throttling the opening therein, a spring tending to maintain each valve in an open condition, a treble-expression bellows and a bass-expression bellows, adjustable distending spring mechanism associated with each expression-bellows, a channel leading from each expression-bellows to the main bellows, a channel leading from the treble-regulating chamber to the treble-expression bellows, a channel leading from the bass-regulating chamber to the bass-expression bellows, a valve associated with each channel leading from an expression-bellows to a regulating-chamber, said valve serving to regulate the openings in their associated channels, means for correspondingly regulating all of said valves, means for independently controlling the valve associated with the channel leading from the treble-regulating chamber to the main bellows, and means for independently controlling the valve associated with the channel leading from the bass-regulating chamber to the main bellows.

15 19. In an automatic piano-player, the combination with a foundation-board, of a main bellows mounted thereon, a treble-regulating chamber and a bass-regulating chamber mounted on said foundation-board, a channel leading from each of said regulating-chambers through the foundation-board to said main bellows, mechanism for throttling the opening in each of said channels, a second passage-way leading from each of said regulating-chambers to said main bellows, and expression-regulating means included in each of said second passage-ways.

20 20. In an automatic piano-player, the combination with motor means for driving and rewinding a suitable note-sheet, of a main bellows, an action-chamber, there being suitable channels leading from said action-chamber to said main bellows, valves for closing said channels, a motor-regulating bellows having

a channel leading to said main bellows, said channel having two openings into said motor-regulating bellows, an automatic regulating-valve for one opening, and a manually-controlled valve for the other opening, and mechanism for simultaneously closing all of the first said valves and opening the manually-controlled valve.

21. In an automatic piano-player, the combination with motor means for driving and rewinding a suitable note-sheet, of a main bellows, action-chambers, main channels leading from said main bellows, one directly to each action-chamber, valves for closing said main channels, a motor-regulating bellows having a channel leading to said main bellows, said channels having two openings into said motor-regulating bellows, an automatic regulating-valve for one opening and a manually-operative valve for the other opening, means for independently closing any one of the main-channel valves, an actuating-lever, and mechanism associated with said lever for simultaneously closing all of the main-channel valves and at the same time opening the manually-controlled valve for one of the openings to said motor-regulating bellows.

22. In an automatic piano-player, the combination with motor means for driving and rewinding a suitable note-sheet, of a foundation-board, a main bellows mounted on said foundation-board, a motor-regulating bellows mounted on said foundation-board, there being a channel having an opening into said main bellows and two openings into said motor-regulating bellows, a normally closed valve for one of said openings into the motor-regulating bellows, and a valve for the other opening carried by the backboard of the bellows, adjustable spring mechanism tending to maintain the motor-regulating bellows in an open condition, action-chambers, main channels leading from said main bellows one to each action-chamber, valves for closing said main channels, means for independently closing any one of said main-channel valves, and mechanism for simultaneously closing all of the valves in said channels at the same time opening the normally closed valve associated with the second opening to said regulating-bellows.

23. In an automatic piano-player, the combination with motor means for driving and rewinding a suitable note-sheet, of a main bellows, a passage-way connecting the main bellows with said motor means, a regulating-bellows for automatically throttling the opening through said passage-way, and manually-controlled means for throwing said regulating-bellows out of commission, thereby permitting the free passage of air from said motor means to said motor-bellows.

24. In a device of the class described, the combination with a plurality of action-valves, of a primary pneumatic for controlling each valve, a primary-pneumatic block upon which

each primary pneumatic is mounted, a primary-pneumatic rack having a plurality of steps, a row of primary-pneumatic blocks mounted side by side upon each step of said rack, the primary-pneumatic blocks on one step of the rack being offset with respect to the pneumatic blocks on another step of the rack, channels connected with the primary-pneumatic blocks and leading from the front wall of each step through the rack and to the tracker-board, and screws for removably securing the blocks to the front walls of the steps.

25. In a device of the class described, the combination with a plurality of action-valves, of a primary pneumatic for each valve, a primary-pneumatic block upon which each primary is mounted, said blocks being grouped in horizontal rows disposed above and behind each other whereby each block may be independently removed.

26. In a device of the class described, the combination with a plurality of action-valves grouped in horizontal rows disposed above and behind each other, of a primary pneumatic for controlling each valve, a primary-pneumatic block for each primary pneumatic, said blocks being also grouped in horizontal rows disposed above and behind each other whereby corresponding valves and primary pneumatics are disposed one below another.

27. In a device of the class described, the combination with a main bellows, of a regulating-chamber, a main channel leading from the main bellows to the regulating-chamber, a valve for controlling the passage of air through said main channel, an auxiliary passage-way from said main bellows to the regulating-chamber, an expression-bellows interposed in said auxiliary passage-way, a valve-opening in the base of said expression-bellows, a valve secured to the movable wall of said bellows tending upon collapse of bellows to throttle said opening whereby to throttle the passage of air through said bellows, a spring 117 secured to the rear wall of the bellows and to the movable wall thereof for resisting said throttling action, and a screw 119 for adjusting the resisting strength of said spring.

28. In a device of the class described, the combination with a main bellows, of a regulating-chamber, a main channel leading from the main bellows to the regulating-chamber, a normally open valve in said main channel, an auxiliary passage-way leading from said main bellows to said regulating-chamber, a normally open valve at the outlet of said auxiliary passage-way into said regulating-chamber, an expression-bellows interposed in said auxiliary passage-way, means upon passage of air through said expression-bellows tending to throttle the passage of air therethrough, adjustable means for resisting said throttling action, means for independently closing the valve in said main channel whereby all the air

from said regulating-chamber passes through the expression-bellows, and means for simultaneously closing said valve in the main channel and said valve at the outlet of the auxiliary channel.

29. In a device of the class described, the combination with treble and bass regulating chambers, of a main bellows for exhausting air from said regulating-chambers, main passage-ways leading from said main bellows to each of said regulating-chambers, normally open valves at the outlets of said main channels, an auxiliary passage-way from said main bellows to each of said regulating-chambers, normally open valves at the outlets of said auxiliary passage-ways, an expression-bellows interposed in each auxiliary passage-way, means upon passage of air through said expression-bellows tending to throttle the passage of air therethrough, means associated with each expression-bellows for lessening said throttling action and for controlling the degree of throttling, means for independently closing either of the main channels whereby all the air passes through the expression-bellows, and means for simultaneously closing all the valves in the main channel and the valves at the outlets of the auxiliary passage-ways.

30. In a device of the class described, the combination with a main bellows, of a regulating-chamber, a main channel leading from said bellows to said regulating-chamber, a normally open valve in said channel, a motor associated with said device, a motor-controlling bellows connected with said motor and with said main bellows, a normally closed valve in said motor-controlling bellows, and means for simultaneously closing the valves in said main channel and opening said valve in the motor-controlling bellows.

31. In a device of the class described, the combination with a main bellows, of a regulating-chamber, a main channel leading from the main bellows to the regulating-chamber, a normally open valve for controlling the passage of air through said main channel, a motor associated with said device, a motor-controlling bellows connected with said motor, a passage-way connecting said motor-controlling bellows with said main bellows, said passage-way having two outlets into said motor-controlling bellows, a normally closed valve over one of said outlets, means upon passage of air through said motor-bellows tending to throttle the other opening of said passage-way, means for preventing complete closure of said other opening, additional adjustable means for controlling the degree of throttling and means for closing the valve in said main channel and for opening the normally closed valve in the motor-controlling bellows whereby air may pass unimpeded from said motor to said main actuating-bellows.

32. In a device of the class described, the

combination with a driving-motor, of a main actuating-bellows, a motor-controlling bellows connected with said motor, a channel connecting said controlling-bellows with said 5 main bellows, said channel having two outlets into said controlling-bellows, a normally closed valve over one of said openings, a second valve tending upon collapse of said controlling-bellows to close the second opening, 10 spring means 103 connected with the movable part of said controlling-bellows for controlling the degree of throttling, and means for opening said normally closed valve whereby unimpeded passage of air is permitted from said 15 motor and through said controlling-bellows to the main bellows to cause increased speed of the motor.

33. In a device of the class described, the combination with a main bellows, of a treble 20 and a bass regulating chamber, main passage-ways connecting said main bellows with said regulating-chambers, valves for said passage-ways normally held open by spring mechanism, an auxiliary passage-way from said main 25 bellows to each regulating-chamber, a valve at the outlet of each auxiliary passage-way into the corresponding regulating-chamber, spring means tending normally to hold said valves in open condition, an expression-bellows interposed in each auxiliary passage-way, a motor 30 associated with said device, a motor-controlling bellows connected with said motor and with said main bellows, a normally closed valve in said motor-controlling bellows, an actuating-arm extending from each of said 35 valves, an independent crank-arm mechanism connected with each valve controlling the main channels connecting the regulating-chambers with the main bellows whereby said passage-ways may be independently controlled, and a 40 common crank-arm mechanism for all said valves, actuation of said crank-arm causing closure of the valves controlling the passage of air into said regulating-chambers and causing opening of the valve in the motor-controlling bellows.

In witness whereof I hereunto subscribe my name this 24th day of May, A. D. 1904.

AXEL F. LARSON.
